UNITED STATES PATENT OFFICE.

BURNHAM C. STICKNEY, OF ELIZABETH, NEW JERSEY, ASSIGNOR TO UNDERWOOD
TYPEWRITER COMPANY, OF NEW YORK, N. Y., A CORPORATION OF DELAWARE.

TYPE-WRITING MACHINE.

1,108,805.

Specification of Letters Patent. Patented Aug. 25, 1914.

Application filed April 28, 1913. Serial No. 763,974.

To all whom it may concern:

Be it known that I, BURNHAM C. STICKNEY, a citizen of the United States, residing in Elizabeth, in the county of Union and State of New Jersey, have invented certain new and useful Improvements in Type-Writing Machines, of which the following is a specification.

My invention relates to typewriting machines and is particularly related to mechanism by which the feed or pressure rolls, which usually bear against the platen in such machines, may be moved to and from said platen.

My invention is herein disclosed as applied to an Underwood typewriting machine in which the platen is journaled in a traveling carriage, and the types strike against the front of said platen while the feed or pressure rolls lie beneath said platen, so that a work-sheet may be passed around said platen from the back and fed up in front past the printing point by said rolls. Said rolls comprise front and rear rolls, which may be held against said platen by any usual or suitable springs. These springs normally hold the rolls against the platen, and said rolls may be moved from the platen or cast off by means of a handle or finger-piece which operates a rock shaft extending beneath the platen adjacent to the rolls. Said rock shaft is journaled on the rock arms on which one set of said rolls are carried; and when said shaft is turned by said handle, tappets or cams fast on said shaft may engage rock arms carrying the other rolls, and thereby swing all of said rolls from the platen.

Other features and advantages will hereinafter appear.

In the accompanying drawings, Figure 1 is a perspective view of the shift frame of an Underwood typewriting machine, showing my invention as applied thereto. Fig. 2 is a section of the same with the rolls bearing against the platen. Fig. 3 is a section, showing the rolls cast off from the platen.

In the Underwood typewriting machine, a platen shift frame comprising ends 1 and 2

includes a paper table 3 over which a work-sheet is inserted, so that the work-sheet passes down and under the usual platen 4 and in so doing passes rear feed rolls 5 and front feed rolls 6, after which the work-sheet passes up in front of the platen to the printing line thereof. The rolls 5 are carried on a shaft 7, which shaft is supported on arms 8 journaled on a rod 9 which extends from end to end of the shift frame and is made fast in the ends 1 and 2 of said frame.

The front feed rolls are carried on a shaft 10, which is supported on arms 11 journaled on the rod 9. The rolls, both front and rear, are normally held pressed against the platen by means of suitable springs 12, which may encircle said rod 9, and may be adjusted as seen at 13. Each of the arms 11 on which the front feed rolls 6 are carried includes an extension 14 extending rearwardly from the rod 9. Each of the arms 8 on which the rear feed rolls 5 are carried also includes an extension 15 extending forwardly. These arms may be forcibly separated by means of a rock arm or tappet 16 fast on a shaft 17 journaled in the extension 14 of the arms 11. When so separated, the rolls 5 and 6 are positively moved away from the platen. The shaft 17 is rocked to thus move said feed rolls away from the platen by means of a rock arm 18 fast thereon, to which is attached a link 19, depending from an arm 20 fast on the shaft 21 of a finger-piece 22 journaled in the end 1.

As is best shown, by comparing Figs. 2 and 3, it will be seen that depression of the finger-piece 22 will raise the rock arm 16, and thereby force the extensions 14 and 15 away from each other, thus moving the rolls 5 and 6 from the position seen at Fig. 2 to the position seen at Fig. 3, in which latter position they are standing at a considerable distance from the platen.

The rock arms 16, which engage the extensions 15, preferably carry rolls 23, forming the tappet engaging portions, which ride on the surfaces of said extensions when the finger-piece 22 is operated. When the fin-

ger-piece 22 is fully depressed, as seen at Fig. 3, the rolls 23 ride into depressions 24 in the extensions 15, and coöperate with said extensions, so as to detain the rolls 5 and 6 in their cast off position.

The rolls 5 and 6 may be prevented from moving too far away from the platen by means of a stop 25 formed as a bar passing through the rod 9, and bent upward on each side thereof, so as to underlie the shafts 7 and 10 on which the rolls 5 and 6 are carried.

Variations may be resorted to within the scope of the invention, and portions of the improvements may be used without others.

Having thus described my invention, I claim:

1. In a typewriting machine, the combination with a rotatable platen and rolls movable to and from said platen, of arms on which said rolls are carried, a rock shaft journaled on one set of said arms, a rock arm fast on said shaft, and means for rotating said shaft to cause the rock arm thereon to cast off said rolls from the platen.

2. In a typewriting machine, the combination with a rotatable platen and front and rear pressure rolls therefor, of arms on which said rolls are respectively carried, extensions on said arms, a shaft journaled on one set of said extensions, a rock arm fast on said shaft arranged to strike an extension of the other set, and means to turn said shaft to separate said extensions and swing said rolls away from the platen.

3. In a typewriting machine, the combination with a rotatable platen and pressure rolls therefor, of a platen frame, a rod in said frame, arms journaled on said rod on which said rolls are carried, a shaft journaled on one set of said arms, a tappet fast on said shaft coöperating with an arm of the other set, and a finger-piece for rotating said shaft to force said arms apart and move said rolls from the platen.

4. In a typewriting machine, the combination with a rotatable platen and front and rear pressure rolls therefor, of arms on which said rolls are respectively journaled, a shaft journaled on one set of said arms, a rock arm fast on said shaft coöperating with an arm of the other set, a finger-piece whereby said shaft may be rocked to swing said rock arm against said last-named arm, and means for locking said rock arm in its position when so swung.

5. In a typewriting machine, the combination with a rotatable platen and front and rear pressure rolls therefor, of arms on which said rolls are respectively journaled, a shaft journaled on one set of said arms, a rock arm fast on said shaft coöperating with an arm of the other set, a finger-piece where-

by said shaft may be rocked to swing said rock arm against said last-named arm, means for locking said rock arm in its position when so swung, and stops limiting the throw of said pressure rolls.

6. In a typewriting machine, the combination with a rotatable platen, of pressure rolls, springs normally holding said pressure rolls against said platen, arms on which said pressure rolls are carried, a shaft journaled on one set of said arms, and a rock arm fast on said shaft coöperating with an arm of the other set, to move said rolls away from said platen.

7. In a typewriting machine, the combination with a rotatable platen, of pressure rolls, springs normally holding said pressure rolls against said platen, arms on which said pressure rolls are carried, a shaft journaled on one set of said arms, a rock arm fast on said shaft coöperating with an arm of the other set, to move said rolls away from said platen, and means for locking said rolls away from said platen.

8. In a typewriting machine, the combination with a rotatable platen, of pressure rolls therefor, pivoted arms carrying said pressure rolls, a shaft journaled on one set of said arms, a rock arm carrying a roller bearing against an arm of the other set, and means for swinging said shaft, to separate said arms and move said rolls away from the platen.

9. In a typewriting machine, the combination with a rotatable platen, of pressure rolls therefor, pivoted arms carrying said pressure rolls, a shaft journaled on one set of said arms, a rock arm carrying a roller bearing against an arm of the other set, means for swinging said shaft, to separate said arms and move said rolls away from the platen, and a notch in said last-named arm in which said roller is detained.

10. In a typewriting machine, the combination with a rotatable platen, of pressure rolls therefor, pivoted arms carrying said pressure rolls, a shaft journaled on one set of said arms, a rock arm carrying a roller bearing against an arm of the other set, means for swinging said shaft, to separate said arms and move said rolls away from the platen, a notch in said last-named arm in which said roller is detained, and stops limiting the throw of said rolls.

11. In a typewriting machine, the combination with a rotatable platen and rolls movable to and from said platen, of arms on which said rolls are carried, a rock shaft journaled on one set of said arms, a rock arm fast on said shaft, and a finger-piece for rotating said shaft to cause the rock arm thereon to cast off said rolls from the platen.

12. In a typewriting machine, the combi-

nation with a rotatable platen and front and rear pressure rolls therefor, of arms on which said rolls are respectively carried, extensions integral with said arms, a shaft journalized on one set of said extensions, a rock arm fast on said shaft arranged to strike an extension of the other set, and

means to turn said shaft to separate said extensions and swing said rolls away from the platen.
